UNITED STATES PATENT OFFICE.

FRANK DUTCHER, OF VERSAILLES, PENNSYLVANIA, ASSIGNOR TO CENTRAL RAILWAY SIGNAL COMPANY, OF PITTSBURGH, PENNSYLVANIA, A CORPORATION OF NEW JERSEY.

RAILWAY SIGNAL-TORPEDO.

1,190,987.

Patented July 11, 1916.

Application filed October 8, 1915. Serial No. 54,874.

To all whom it may concern:

Be it known that I, FRANK DUTCHER, a citizen of the United States, residing at Versailles, in the county of Allegheny and State of Pennsylvania, have invented certain new and useful Improvements in Railway Signal-Torpedoes, of which the following is a specification, reference being had therein to the accompanying drawing.

10 This invention relates to improvements in railway signal torpedoes and is of that type which is composed of paper and has a body portion with a cavity to receive a plastic compound, the body portion having also 15 inwardly folding flaps.

The object of my present invention is to provide an improved manner of constructing the flaps to facilitate the attachment of the rail-attaching strap, and the several 20 parts so constructed that the flaps serve to lock the strap and the strap to lock the flap.

In the accompanying drawings, Figure 1 is an inverted perspective view of a torpedo embodying my invention. Fig. 2 is a cross sectional view of the same showing the torpedo applied to a railroad rail. Fig. 3 is a 25 bottom plan view of the torpedo with the sealing sheet or patch shown in dotted lines. Fig. 4 is a perspective view showing the 30 parts of the improved torpedo in separated relation.

The case composing the torpedo comprises a central portion 1 which is shaped to form a cavity 2 to receive a correspondingly 35 shaped plastic tablet 3. This central portion 1 is provided with a laterally extending surrounding flange 4, and formed integral with this flange are oppositely arranged inwardly folding flaps 5 which together when 40 folded in have a corresponding shape to fit or register with the shape of the flange 4. The plastic explosive 3 is placed within the recess 2 and is surrounded by a suitable waterproof coating 6. A disk 7 is here 45 shown as being placed over the plastic compound and extending out and fitting on the flange 4. This disk 7, however, may or may not be used. When it is used, it is arranged as just stated, and as shown in Fig. 2. 50 A second disk 8 is provided with strap openings 9 through which a suitable rail-engaging strap 10 is threaded. When the disk 7 is used, this disk 8 is placed outside of and against the disk 7, but when the disk 7 is 55 not used, the disk 8 is placed in direct con-

tact with the explosive. All of these parts are cemented together with the strap in position through the openings of the disk 8.

Each of the flaps 5 is provided with a strap receiving opening 11, and a V-shaped notch 12 is made in the edge of each of the flaps 5, and this notch extends to and has its apex communicating with the said slots 11. The object of this arrangement is that after the disk 8 is in position with the strap 10 carried thereby, then the flaps 5 are folded inwardly and will embrace the strap by deflecting either one or both of the points 13 of the flaps which are formed by the notches 12 communicating with the slots 11. Where the strap is threaded through a disk 8 that is inside of the flaps when they are folded, it would be practically impossible to thread the strap through the openings 11, and hence the notches 12 communicate with the slots 11, so that the straps may be placed within the slots 11 by deflecting the corners 13.

After the parts just described are placed in position and cemented, then a sealing 80 sheet or flap 14 is placed over the center of the bottom of the torpedo, as shown in Fig. 1, and this will seal the opening 15 formed by the notches 12.

A torpedo constructed as described is 85 without any metal parts to hold the rail-engaging strap in position while at the same time the folding flaps are locked and held, the strap 10 and sealing flap 14, and the strap is held by the flaps.

Having thus fully described my invention what I claim and desire to secure by Letters Patent is:

1. A railway signal torpedo comprising a fibrous case having a central portion with an explosive receiving recess, the central portion having an annular laterally projecting flange and oppositely extending integral inwardly folding flaps, an explosive within the recess, a disk having strap receiving openings, a strap passing through the said openings, the said flaps having strap openings, and passage ways extending from the outer edges of the flaps inward, and communicating with the said strap receiving openings, the disk and the flaps being cemented together and to the central portion.

2. An improved railway signal torpedo comprising a case having a central portion

provided with an explosive receiving cavity, a surrounding laterally extending flange and integral inwardly folding flaps, an explosive within the cavity, a disk having strap openings, the disk fitting over the explosive and the said flange, the flaps having strap openings, and the outer edges of the flaps provided with V-shaped notches communicating with the strap openings for the purpose described, the flaps and the disk cemented together and to the central portion.

3. An improved railway signal torpedo comprising a central portion having an explosive receiving recess, a surrounding laterally projecting flange and integral oppositely arranged inwardly folding flaps, an

explosive within the recess, a disk fitting over the explosive and against the flange, and cemented thereto, a second disk having strap openings, a strap passing through the said openings, the second disk placed upon and cemented to the first-mentioned disk, the said flaps having strap openings, and V-shaped connecting passage ways for the said openings, the flaps folded inwardly and cemented to the said second disk.

In testimony whereof I hereunto affix my signature in the presence of two witnesses.

FRANK DUTCHER.
